(57) **CLAIM**

We claim the ornamental design for an audio/video communications device, as shown and described.

DESCRIPTION

FIG. 1 is a perspective view of the audio/video communications device showing my novel design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The light, broken lines in the drawing represents contours, and are part of the claimed design.
